Philip S. McKee. ATTORNEY

UNITED STATES PATENT OFFICE.

HUGO GERNSTBACK, OF NEW YORK, N. Y., ASSIGNOR TO RADIO INDUSTRIES CORPORATION, OF NEW YORK, N. Y., A CORPORATION OF NEW YORK.

TUNED TELEPHONE RECEIVER.

Application filed March 17, 1923. Serial No. 625,702.

To all whom it may concern:

Be it known that I, HUGO GERNSTBACK, a citizen of the United States of America, and a resident of New York city, county and State of New York, have invented certain new and useful Improvements in Tuned Telephone Receivers, of which the following is a specification.

In the use of telephone receivers, particularly for radio purposes, it has been found that the best results are obtained when two receivers of a head set are matched in tone.

One of the important objects of this invention is to enable the matching or pairing of the receivers in a simple and practical manner and in a way which can be readily performed after the receivers are assembled in condition for use.

Another important object of the invention is to provide a receiver particularly suited for loud-talkers and capable of adjustment to allow for increased action of the diaphragm resulting from "loading" of the actuating magnet.

Further objects of the invention are to effect savings in the cost of construction, to provide better protection for the more delicate parts of the instrument and to improve the acoustic characteristics.

In the accompanying drawing there is illustrated a practical embodiment of the invention, wherein the foregoing and other objects are attained, but it is to be understood that the structure may be modified in various respects without departure from the broad spirit and scope of the invention as hereinafter defined and claimed.

Figure 1 in the drawing referred to is a perspective view of one of the receivers with parts broken away and appearing in section; Figure 2 is an enlarged cross sectional broken view; Figure 3 is a fragmentary sectional view similar to Figure 2, showing the diaphragm adjusted in closer relation to the magnet; Figure 3^a is a broken section illustrating the diaphragm adjusted to a greater degree of clearance as for use in loud-talker operation; Figures 4, 5 and 6, are fragmentary sectional views of modified forms of the resilient diaphragm support.

The case of the instrument is shown in the form of a cup 5 closed at the back and having an ear cap or cover 6 adjustably at-

tached over the front or open side of the same by a screwthreaded joint 7.

The actuating magnet 8 which is housed within the case is shown as of tripolar construction having a centrally disposed polar projection 9 and two side pole pieces 10.

The diaphragm 11 is supported and adjustably positioned with respect to the actuating magnet by a resilient element shown in the form of a ring 12 of highly elastic material, such as pure Para rubber, interposed between the back of the diaphragm and the rim or edge of the cup. The cap or cover has an interior annular shoulder 13 engaging over the edge of the diaphragm and extending both outwardly and inwardly above the area of contact between the supporting ring and diaphragm so as to provide a firm seat for the diaphragm and enable the application of a compressing force without distortion of the diaphragm. Thus in the illustration it will be seen that by turning the cap down over the case the resilient diaphragm supporting annulus will be compressed and so enable a very exact adjustment of the diaphragm toward the magnet face or faces.

In the first form of the invention illustrated the diaphragm supporting ring is shown as substantially T-shape in cross section, with a head having a decidedly rounded crown, flat at the under side for a full bearing on the face of the cup and with the dependent portion seated in an annular groove 14 provided in the face of the cup. The crowned head of the ring is shown as of less width than the face of the cup wall so that it will not under compression expand beyond the edges of the cup. The seating of the dependent rib within the groove holds the supporting ring accurately located under all degrees of compression and this construction also provides a depth of elastic material which allows for the full necessary range of adjustment of the diaphragm.

In the present disclosure I have illustrated several of the different ways in which the resilient diaphragm support may be constructed. In the first modification illustrated in Figure 4, the head or contacting face of the support is ribbed as indicated at 15 to increase the resiliency at this point.

In Figure 5 the resilient diaphragm supporting ring is positioned by being constructed with a groove 16 in its under side

to fit over a corresponding rib 17 on the face of the case.

In Figure 6 the resilient diaphragm support is illustrated as a ring 18 which is of circular cross section and tubular in form, seated within a substantially semi-circular groove 19.

In all forms the diaphragm support has a range of compressive adjustment at least 10 equal to the difference between the maximum and minimum permissible clearance between the diaphragm and pole face or faces of the actuating magnet. This enables the diaphragm to be set at the best or more 15 effective point within the scale of operative relation to the magnet.

Because of the fact that the diaphragm is positioned by the resilient support it is possible in this invention to face off the 20 magnet poles and the rim or edge of the case in the same plane, substantially as indicated in the drawing. This means that after assembly of the magnets in the cases 25 the magnet poles and cases can both be finished off in a single grinding or facing operation. This construction also results in greater accuracy and efficiency since no minute measurements and adjustments are necessary to establish a finely adjusted 30 relation between the magnet poles and rim of the cup.

It will be seen from the foregoing that by 35 simply turning the ear cap the diaphragm may be adjusted toward or away from the actuating magnet to vary the tone and other characteristics of the receiver. This enables the receivers to be very easily tuned either for the purpose of matching them or for bringing in special signals, such as 40 the higher pitched notes, for instance, which only become audible upon a very close adjustment of the diaphragm. The resilient support provides a practical air-tight seal for the receiver case, preventing rust, 45 corrosion or other injury of the magnet parts. This air-tight construction also appears to improve the acoustic properties, producing a clear agreeable tone, the pitch of which can be readily varied to suit the individual 50 user.

The resilient support gives the diaphragm a freedom of action which particularly suits the receiver to the exacting requirements of 55 loud-talkers, permitting the diaphragm to flex easily and through the necessarily greater ranges required in loud-talker operation and by the simple adjustment disclosed, the diaphragm can be quickly adjusted to increase the spacing so that the diaphragm will vibrate free of the magnet no matter to what extent the magnet is loaded.

Another important feature of the invention disclosed is that in each instance the diaphragm remains in its adjusted relation 65 without provision of set screws or other special holding means, the resiliency of the diaphragm support operating as an automatic lock for retaining the parts in each 70 adjustment.

What I claim is:

1. In telephone receiver, a hollow case, a magnet within the case having a pole piece for actuating the diaphragm, the edge of the case and the face of the pole piece being 75 finished in substantially the same plane whereby both may be faced off in a single operation, a diaphragm overstanding the edge of the case, a resilient support for the diaphragm interposed between the dia- 80 phragm and the edge of the case and a screw cap adjustably engaged with the case over the diaphragm and adapted by its adjustment on the case to compress the resilient support in varying degrees and to thereby 85 adjust the relation of the diaphragm to the pole face of the magnet.

2. In a telephone receiver, a case, a magnet in said case arranged with its pole face in the plane of the edge of the case, a dia- 90 phragm, a resilient support for the dia- phragm seated in the edge of the case and having a range of compressibility sufficient to enable variable spacing of the diaphragm with respect to the magnet through the 95 range of practical operativeness of the magnet and retaining means for the diaphragm adjustable with respect to the case for varying the compression of the resilient dia- phragm support.

3. In a telephone receiver, a casing having an annular wall with a groove in the top face of the same, a diaphragm support of highly resilient material, substantially T-shaped in cross section, having the dependent portion thereof engaged in said groove and the head portion of the same bearing on the top face of the annular wall at opposite sides of the groove therein, a diaphragm bearing on the head portion of said resilient support and a retainer for said diaphragm adjustable with respect to the case for the purpose of varying the compression of the resilient diaphragm support.

4. A combination as in claim 3 in which 115 the head of the T-shaped support is crowned to provide a rounded bearing for the dia- phragm and in which the head portion of such support terminates short of the edges of the face on which it is seated.

In witness whereof, I have hereunto set my hand this 12th day of March, 1923.

HUGO GERNNSBACK.
